(57) **CLAIM**

The ornamental design for a confectionery bottle, as shown and described.

DESCRIPTION

FIG. 1 is a perspective view of a confectionery bottle, showing our new design in a first embodiment;

FIG. 2 is a front view of the embodiment shown in FIG. 1; FIG. 3 is a back view of the embodiment shown in FIG. 1; FIG. 4 is a side view of the embodiment shown in FIG. 1; FIG. 5 is another side view of the embodiment shown in FIG. 1;

FIG. 6 is a top view of the embodiment shown in FIG. 1; and, FIG. 7 is a bottom view of the embodiment shown in FIG. 1.

The broken line disclosure forms no part of the claimed design.

1 Claim, 4 Drawing Sheets
